DRESSING TOOL FOR GRINDING WHEELS

Gerald J. Wallen, San Francisco, Calif.

Application May 18, 1946, Serial No. 670,736

2 Claims. (Cl. 125—37)

1

This invention relates to improvements in tools for dressing the grinding faces of emery wheels.

An object of my invention is to provide an emery wheel dressing tool embodying a novel lubricating system for supplying a lubricant under pressure to the bearing surfaces of the rotatable cutters.

Another object of my invention is to provide an improved tool for dressing grinding wheels, embodying novel adjustable means for maintaining the cutters in properly aligned relationship irrespective of the wear thereof during the normal operation of the device.

A further object of my invention is to provide an improved dresser for grinding tools having a construction which by reason of the novel features it possesses is capable of operating efficiently for a considerably longer time than is possible with similar tools of the type now commonly used.

Other and further objects of my invention will be pointed out hereinafter, or will be indicated in the appended claims or will be obvious to one skilled in the art upon an understanding of the present disclosure.

For the purpose of this application I have elected to show herein certain forms and details of a dresser for grinding wheels representative of my invention, it is to be understood, however, that the embodiment of my invention herein shown and described is for the purpose of illustration only and that therefore it is not to be regarded as exhaustive of the variations of the invention.

In the accompanying drawings:

Fig. 1 is a side elevation of a tool for dressing emery wheels embodying my invention, showing parts thereof in section;

Fig. 2 is side elevation of the tool as viewed from another side, showing certain parts broken away and in section;

Fig. 3 is a perspective view of one of the cutters, showing the means for maintaining them in interconnected and fixed relationship;

Fig. 4 is a perspective view of the adjustable boss; and

Fig. 5 is an enlarged sectional view taken through the head of the device.

Referring to the drawings the numeral 1 designates a carrier head formed with suitably spaced arms 2 and 3 which are provided with opposed threaded holes one having an adjustable boss 4 and the other a stationary boss 5 positioned therein. The boss 4 is formed with a spindle or shaft 6 which extends into an axial socket

2

or recess 7 in the other boss 5. The boss 4 is formed with an annular shoulder 8 at one end of the spindle 6 and through the adjustment of the said boss the intervening space between the inner end of the stationary boss 5 and the shoulder 8 may be shortened or lengthened for the purpose herein later described. A set screw 9 extending through the head portion of the boss 4 and engageable with the outer surface of the arm 3 normally holds the said boss against turning after it has been once adjusted.

Rotatably journaled on the spindle 6 is a tubular bushing 10 upon which are mounted a plurality of disc-like cutters 11 formed in the usual manner with uniformly spaced teeth. The cutters may be mounted for independent rotation, but in the particular example illustrated on the drawings they are shown as being secured together by interconnecting tongues 12 and grooves 13. When secured together the cutters may be held in positions wherein their teeth are transversely staggered, thereby avoiding the cutting of parallel grooves in the grinding surface of an emery wheel during a dressing operation. When the cutters become worn, through extensive use they are apt to develop a side play and fail to retain their accurate alignment. In such an event the boss 4 may be adjusted inwardly to again bring the cutters into suitable relative positions with respect to each other. The tubular bushing 10 is slightly shorter than the length of the combined axial bearing surfaces of the cutters 11, thereby allowing the relative adjustment of the bosses to be made after the cutters have become worn and require closer contact with one another. The boss 5 is preferably formed with left hand threads which do not permit its being unscrewed when the cutters are rotated in the usual way.

Secured as by threaded means to the head 1 is an elongated tubular handle 14 within which a supply of lubricant, such as heavy bodied grease, is normally held. At the outer end of the tubular handle 14 is firmly secured an end member 15 having a reduced end extension around which is formed an annular groove 16. A rotatable hand piece 17 is normally held in connected and rotatable relationship with respect to the end member 15 by means of a screw 18 extending into the annular groove 16. Rigidly secured as by a pin 19 or other means to the hand piece 17 is an elongated screw 20 which loosely extends through an axial opening in the end member 15. The screw 20 extends substantially the length of the tubular handle 14. The piston which the screw

55

20 actuates to eject the lubricant from the tubular handle comprises an internally and externally threaded tubular member 21 through which the elongated screw 20 extends and operatively engages. Mounted on the tubular member 21 are opposed leather cup-washers 22 which are held in separated positions by a flat spacing disc. A spacing ring 23 holds the sides of one of the washers 22 against inward movement while a head on the tubular member 21 performs the same function with respect to the other washer. A nut 24 screwed on the tubular member 21 holds the spacing ring, the washers and the tubular member in securely assembled relationship. The inherent resiliency of the washers 22 maintains them in firm contact with the walls of the tubular handle 14 and thereby prevents the piston from being rotated when the elongated screw 20 is turned. Spring means may be provided for this purpose also. By turning the hand piece 17 in a certain direction the lubricant is discharged from the tubular handle 14.

In replenishing the supply of lubricant in the tubular handle 14 the head 1 is first detached, and thereafter the screw 18 is removed to permit the relative separation of the said handle and the hand piece 17. After the detached end of the tubular handle 14 is inserted in a supply of lubricant, the hand piece is pulled outwardly with one hand while the tubular handle is held by the other hand in a stationary position. The piston is thereupon pulled outwardly from a position near the discharge end of the tubular handle 14 to a position near its opposite end, thereby drawing the lubricant up into the said handle. After the tubular handle is again connected to the head, the elongated screw 20 is turned until the hand piece 17 is in a position where it can be connected by the screw 18 to the end member 15. When the hand piece is again connected to the end member, the piston may be actuated to discharge the lubricant from the tubular handle 14 through a duct 25 and into an annular channel 26 formed on the boss 5. The lubricant is conducted through one or more radial openings 27 in the boss 5 to the outer end of the axial socket 7. A longitudinal axial passage 28 in the spindle 6 is connected to the axial socket 7, and one or more radial ducts 29 in the said spindle connects the axial passage 28 with a longitudinally disposed groove 30 on the outer bearing surface of the spindle. The tubular bushing 10 is provided with one or more openings 31 which connects the groove 30 with the bushing's outer bearing surface. Thus, when the lubricant is discharged by the piston from the tubular handle 14 it proceeds through the duct 25, the annular channel 26, the radial openings 27, the unoccupied portion of the recess or socket 7, the axial passage 28, the radial ducts 29 to the longitudinal groove 30 in the bearing surface of the spindle 6. Some of the lubricant is conveyed from the longitudinal groove 30 through the openings 31 to the outer bearing surface of the bushing. The lubricant is distributed along the inner and outer bearing surfaces of the bushing 10, and some of it reaches the contacting surfaces of the cutters 11.

Since the passages leading from the tubular handle 14 to the bearing surfaces of the cutters and bushing are somewhat restricted because of their comparatively small size, a continuous flow of the lubricant to the said bearing surfaces may be insured during the operation of the dresser if the hand piece 17 is turned occasionally to maintain a pressure on the body of lubricant in

the tubular handle. The movement of the lubricant in a direction away from the bearing surfaces tends to avoid at least a substantial proportion of the particles coming from an emery wheel during a dressing operation from reaching the said bearing surfaces. Through the aforesaid adjustments and by maintaining a generous supply of lubricant at the bearing surfaces at all times during the operation of the device the operating lives of the cutters, spindle and bushing are prolonged at least until the teeth of the cutters are substantially worn away.

What I claim is:

1. In a tool for dressing grinding tools, a bifurcated head having aligned threaded openings arranged in opposed relation, a normally stationary boss secured in one of the openings and having an axial socket, an annular groove and a radial channel connecting the socket and the groove, an adjustable boss secured in the other threaded opening of the head and having an elongated axial shaft extending into the socket of the other boss the said shaft having a longitudinal channel and a radial passage extending from the said longitudinal channel to the bearing surface of the shaft, a plurality of cutters journaled on the shaft, and means for supplying lubricant under pressure, to the annular groove of the stationary boss, whereby the bearing surfaces of the cutters may be lubricated.

2. In a tool for dressing grinding wheels, a bifurcated head having opposed threaded openings and a duct leading from a lubricant reservoir mounted on the head to one of the threaded openings, a normally stationary boss secured in the last mentioned threaded opening and having an annular groove positioned to receive lubricant supplied by the duct, the said boss having also an axial socket and one or more radial channels connecting the socket and the annular groove, an adjustable boss secured in the other threaded opening of the head and having an elongated axial shaft extending into the socket of the stationary boss, the said shaft having a longitudinal channel and one or more radial passages extending from the said longitudinal channel to the bearing surface of the shaft, a bushing journaled on the shaft and having one or more passages for conveying lubricant from the bearing surface of the shaft to the outer bearing surface of the bushing, a plurality of cutters journaled on the bushing and arranged in positions whereby their engagement one with another may be secured by the adjustment of the adjustable boss, and means for forcing lubricant under pressure from the reservoir through the duct in the head, whereby lubricant may be supplied to the bearing surfaces of the shaft, the bushing and the cutters.
